UNITED STATES PATENT OFFICE.

LOUIS W. THOMPSON, OF WILKINSBURG, PENNSYLVANIA, ASSIGNOR TO GENERAL ELECTRIC COMPANY, A CORPORATION OF NEW YORK.

REGULATOR.

1,251,446.

Specification of Letters Patent. Patented Dec. 25, 1917.

Application filed March 22, 1913, Serial No. 756,066. Renewed April 29, 1916. Serial No. 94,518.

To all whom it may concern:

Be it known that I, LOUIS W. THOMPSON, a citizen of the United States, and a resident of Wilkinsburg, in the county of Allegheny and State of Pennsylvania, have invented 5 a new and useful Improvement in Regulators, of which the following is a specification.

My invention relates to regulators that 10 are adapted to be employed in connection with dynamo electric machines for automatically regulating the effect of a resistance by intermittently short-circuiting the same. It has particular reference to regulators of the vibrating type which effect the regulation of generator voltage by controlling the field strength of the generators.

Electric regulators of the vibrating type have long been used for controlling the field 20 current of dynamo-electric machines for the purpose of controlling their operation as regards speed, voltage, load, power factor, etc. One of the chief difficulties encountered in the use of this type of regulator is an excessive 25 sparking at the contacts, which ultimately so injures these contacts that their operation is imperfect and unsatisfactory. Large contacts cannot be satisfactorily used because of the increase in weight. This difficulty is commonly overcome by using a 30 plurality of synchronously operated relays, each of which short-circuits only a portion of the whole resistor, so that the potential difference across each pair of contacts is 35 reduced. Further difficulty has been encountered in so arranging the moving contacts that the surges technically known as "hunting" are prevented.

My invention comprises a regulator of 40 the vibrating type in which sparking at the contacts is prevented, while the use of a plurality of relays is avoided. To this end I short circuit a resistor by means of alternative, or transfer, circuits, each of which comprises a periodic circuit interrupter of 45 rugged construction in series with vibratory contacts. The vibration of said contacts is effected and controlled jointly by the quantity to be regulated, and by the periodic circuit interrupter. These devices are so arranged that said alternative, or transfer, circuits are always broken by the periodic circuit 50 interrupter.

A further object of my invention is to 55 provide a novel and improved arrangement

for the prevention of "hunting." For this purpose I provide, in connection with the combination of vibrating contacts a periodic circuit interrupter, a resilient member tending, when stressed, to open the vibrating 60 contacts and a device for stressing said resilient member which is set in action upon the closing of the circuit through said device and put out of action by the opening of the periodic circuit interrupter. 65

The single figure of the drawings is a diagrammatic view of circuits and apparatus showing my invention as applied to the regulation of the voltage of an alternating current generator through regulating 70 the field current of its exciter.

Referring to the drawings, an electrical circuit, the voltage of which it is desired to maintain substantially constant, comprises line conductors 1 and 2, and is supplied 75 from an alternating current generator 3. The field winding 4 of the generator is energized by an exciter 5 which is here indicated as a direct current shunt wound generator. 80

The exciter 5 is provided with a shunt field winding 6 and a field resistor 7 in series therewith. The main circuit of the exciter comprises a variable resistor 8 which may be adjusted to control the current in 85 the circuit.

My regulator, as shown, comprises means for intermittently short circuiting the field resistor for varying lengths of time, depending upon an electrical condition of the circuit including the conductors 1, 2. Said means comprise relatively movable contacts, which may have any one of a variety of forms, but, as illustrated, comprise resilient switch members 9 and 10, the extremities of 90 which are provided with contact members which coact respectively with pairs of contact members 11, 12 and 13, 14. The switch members 9 and 10 are actuated by movable members 15 and 16, respectively, and are 95 adapted, due to their yielding character, to permit some movement of the members 15 and 16 after engagement of the contact members 11, 12 and 13, 14 respectively. 100 The core members are each provided with two coils 17 and 18.

The coils 17 are in series with each other and with the secondary winding 19 of a voltage transformer 20, the primary winding 21 110

of which is connected across the line of the alternator 3. The coils 18 are connected in series with each other and with the secondary winding 22 of a current transformer 23, the primary winding 24 of which is in series with the line conductor 1. The transformers 20 and 23 are made without cores or with small cores to reduce the inductance and thereby decrease the time required for an impulse to be transmitted by the transformers and render the system more sensitive to changes. The coils 17 constitute what may be termed the main coils and the coils 18 constitute the compensating coils which are employed for reasons that will be hereinafter explained. The core members are also each provided with coils 25 connected respectively to the contact members 11 and 14. The core members, when moved to their lowermost positions upon the energization of the windings 25, compress the springs 26, which serve as buffers and also to impart an upward movement to said cores when the windings 25 are subsequently deenergized.

25 A pair of periodic circuit interrupting devices 27 comprises rotatable drums 28 provided with alternate sections of conducting material 29 and insulating material 30. As here shown, four sections of each material 30 are used, the opposite sections of conducting material being cross-connected in order that oppositely arranged brushes 31 may be connected when sections of conducting material are engaged by the respective brushes. The conductor sections are arranged to project from the wheel in order that, as the drums rotate, a quick break may be obtained at the brushes, which may be yieldingly pressed against the drums 28 by any suitable means.

40 The drums are arranged to be rotated by any suitable source which may be connected to a rotating part of the system or may be independent as desired. It will be noted the drums are arranged to rotate 45 degrees apart in order that one pair of brushes will be in engagement with a pair of contacts on one drum when the other pair of brushes is out of engagement with the contacts on the other drum, the conditions alternating as the 50 drums rotate. The circuit interrupters 27 control the energization of the windings 25 and prevent the disengagement of the contacts carried by the switch members 9 and 10 from contacts 11, 12 and 13, 14 respectively, while current is passing therethrough, and any equivalent construction may, of course, be employed.

The operation of my invention, as at present understood, is as follows: Assume for 60 purposes of explanation that it is desired to maintain the voltage of the circuit 1, 2 at a predetermined value and that the various elements of the system are adjusted for this value. Also disregard for the moment the effect of the compensating windings 18, 18,

which will be hereinafter described. It should be noted that the resistance 7 is of such value that, if it be continually maintained in series with the field winding 6 of the exciter, the voltage of the circuit 1, 2 70 will be less than the desired value, whereas, if a short circuit be continually maintained around said resistance 7, the voltage of the circuit 1, 2 will have a value greater than that desired. If the voltage of the circuit 1, 2 75 be sufficiently high, the cores 15 and 16 will be raised to a position in which the contacts carried by the switch members 9 and 10, secured thereto, will be maintained out of contact with the contacts 11, 12 and 13, 80 14. The resistance 7 will accordingly be rendered effective and hence the voltage of the circuit 1, 2 will decrease. When a certain decrease in voltage has occurred, the core members 15 and 16 will lower so that 85 the contacts carried by the switch members 9 and 10 will engage with the contacts 11, 12 and 13, 14. During the period of such engagement, the resistance 7 will be short circuited through alternative circuits, one of 90 which comprises the conductor 32, contact 12, switch member 9, contact 11, lefthand winding 25, and the left-hand interrupter 27, and the other of which comprises the conductor 32, contact 13, switch member 10, 95 contact 14, right-hand winding 25, and the right-hand interrupter 27. The field current of the exciter will thus be transferred from the circuit comprising one interrupter to the circuit comprising the other interrupter. When the circuit is closed through a winding 25, the core member associated therewith will be drawn down so that it will compress the spring 26 associated therewith and will also flex the switch member 9 105 or 10, as the case may be, causing the contacts carried by the same to firmly engage with the contacts 11, 12 or 13, 14. On the drawing, the switch member 9 is shown flexed in the manner described, since the circuit through the left-hand winding 25 is closed. If now, the voltage of the circuit 1, 2 rise to, or above, the desired value, the increased energization of the windings 17, 17 110 will tend to raise the cores 15 and 16 and lift 115 the contacts carried by the switch members 9 and 10 out of engagement with the contacts 11, 12 and 13, 14. If the interrupters, at the moment the circuit voltage reaches this value, are in the position shown, the contacts carried by the switch member 10 will be raised out of engagement with the contacts 13, 14, but the contacts carried by the switch member 9 will be maintained in engagement with the contacts 11, 12, due to 125 the energization of the left-hand winding 25 which acts to hold the switch member 9 in the position illustrated. However, as soon as the left-hand interrupter moves to a position where the brushes 31 thereof and a 130

pair of contacts 29 thereof are no longer engaged, the combined effect of the left-hand winding 17, the flexed switch member 9 and the spring 26 will cause the contacts carried by the switch member 9 to be thrown out of engagement with the contacts 11, 12. The contacts carried by the switch members 9 and 10 now being out of engagement with their co-operating stationary contacts, the resistance 7 will become effective and the voltage of the circuit 1, 2 will consequently decrease. The cores 15 and 16 will therefore lower and a circuit in shunt to the resistance 7 will be completed through that interrupter, which at the instant has a pair of contacts 29 in engagement with a pair of brushes 31, and the winding 25 in circuit with such interrupter. Assume that, at this instant, the right-hand interrupter has a pair of contacts 29 in engagement with the brushes 31. The shunt circuit will therefore be completed through such right-hand interrupter, the right-hand winding 25, the contact 14, switch member 10, contact 13, and the lead 32. The resistance 7 being short circuited the voltage of the circuit 1, 2 will increase. The right-hand winding 25 being energized, the spring 26 will be compressed and the switch member 10 will be flexed in the manner previously described. In this way the core members 15 and 16 are caused to vibrate vertically, and if the voltage of the circuit 1, 2 is below the desired value, the period, at each vibration, during which a short circuit around the resistance 7 exists is greater than the period during which such a short circuit exists when the voltage of the circuit 1, 2 has the desired value and, on the other hand, if the voltage of the circuit 1, 2 be above the desired value the period during which a short circuit around the resistance 7 exists is less than the period during which such short circuit exists when the voltage of the circuit 1, 2 has the desired value. It is also evident that the switch members 9 and 10 can never be opened until after the respective circuits in which they are included are opened by the interrupter. Thus sparking between the switch members 9 and 10 and their respective contacts is wholly eliminated.

The effect of the compensating coils 18 will now be explained. When a heavy load is thrown on the supply circuit, there will be an increase in the drop in potential due to line resistance. It is usually desirable to maintain a substantially constant voltage at the points of current supply and in order to effect this result, the generator voltage must be increased to compensate for the line drop. The compensating coils 18 are arranged to provide for the necessary modifications of the effects produced by the coils 17. An increase in the flow of current in the line conductor 1 will cause a corresponding in-

crease in the secondary winding 22 of the transformer 23 and in the energization of the coils 18. The coils 18 are so wound that an increase in current has the effect of opposing the upward movement of the core 70 members and, as before explained, the relatively longer period of closure of the switch members 9 and 10 will cause an increase in the generator voltage. When the current decreases, this effect is diminished and when 75 no load is on the line, the compensating coils have no effect. Thus, it will be understood that the coils 17 and 18 have independent effects upon the core members but the resultant effect may be either the sum or difference of the independent effects according to line conditions.

It will be understood that many changes will occur to one skilled in the art. Such changes as fall within the limits of the appended claims may be made without departing from the spirit of my invention.

I claim as my invention:

1. An electric regulator comprising a resistor, relatively movable contacts responsive to the quantity to be regulated, means for holding said contacts in engagement, a periodic circuit interrupter and a circuit for shunting said resistor comprising said contacts, holding means, and circuit interrupter. 90
2. An electric regulator comprising a resistor, relatively movable contacts responsive to the quantity to be regulated, means for holding said contacts in engagement, resilient means put under tension by the action 100 of said holding means, a periodic circuit interrupter, and a circuit for shunting said resistor comprising said contacts, holding means, and circuit interrupter. 95
3. An electrical regulator comprising a 105 resistor, relatively movable contacts responsive to the quantity to be regulated, one of said contacts being resiliently mounted, means for holding said contacts in engagement and putting said resilient mounting under tension, a periodic circuit interrupter, and a circuit for shunting said resistor comprising said contacts, holding means, and circuit interrupter. 110
4. An electric regulator comprising a resistor, two sets of relatively movable contacts, each of which is responsive to the quantity to be regulated, a periodic circuit interrupter in series with each set of contacts, said circuit interrupters being arranged so that one will be open when the other is closed and alternative circuits for shunting said resistor, each of which comprises a periodic circuit interrupter and a pair of contacts. 115
5. An electrical regulator comprising a resistor, a pair of relatively fixed contacts, a pair of movable contacts associated therewith and electrically connected by means of a resilient member, means responsive to 120
6. An electrical regulator comprising a resistor, a pair of relatively fixed contacts, a pair of movable contacts associated therewith and electrically connected by means of a resilient member, means responsive to 125
7. An electrical regulator comprising a resistor, a pair of relatively fixed contacts, a pair of movable contacts associated therewith and electrically connected by means of a resilient member, means responsive to 130

- the quantity to be regulated associated with said resilient member intermediate said contacts, a coil in series with said contacts arranged, when energized, to hold said contacts in engagement and put said resilient member under tension, periodic circuit interrupter, and a circuit for shunting said resistor comprising said contacts, series coil, and circuit interrupter.
10. The combination with a main electrical circuit comprising a generator, of a field winding therefor, means for controlling the excitation of said winding comprising a circuit, said circuit including a periodic circuit interrupter and a switch member that is responsive to the current and the voltage values of said main circuit and to conditions in the circuit of said field winding.
7. The combination with a generator, of a field winding therefor, means for controlling the excitation of said winding comprising a circuit including a periodic circuit interrupter and a switch member responsive to an electrical condition of said generator and conditions in the circuit of said field winding.
8. The combination with a generator having a field magnet winding and a resistor in circuit therewith, of means for shunting said resistor comprising a periodic circuit interrupter, a coil in circuit with said circuit interrupter, and a movable core member actuated by said coil.
9. An electric regulator comprising a resistor, a plurality of periodic circuit interrupters, a plurality of vibratory members, and a plurality of transfer circuits in shunt to said resistor and adapted to be jointly controlled by said circuit interrupters and said vibratory members.
10. An electric regulator comprising a resistor, a pair of circuits in shunt to said resistor, a pair of periodic circuit interrupters adapted to alternately open said circuits, and a pair of vibratory members adapted to be controlled both by the quantity to be regulated and by said interrupters for controlling the continuity of said circuits.
11. An electric regulator comprising a resistor, a pair of circuits in shunt to said resistor, a pair of periodic circuit interrupters adapted to alternately open said circuits, and a vibratory device, associated with each of said circuits, comprising a winding and vibratory contacts, in series therewith, and a winding adapted to be energized in response to the quantity to be regulated.

In testimony whereof, I have hereunto subscribed my name this 20th day of March, 1913.

LOUIS W. THOMPSON.
